Salvatore Bevelacqua, Westport, Conn., assignor to Bevelacqua, Inc., New York, N. Y., a corporation of New York

Application March 3, 1949, Serial No. 1,196

Term of patent 3½ years

(Cl. D5—4)

To all whom it may concern:

Be it known that I, Salvatore Bevelacqua, a citizen of the United States, residing at Westport, Fairfield County, Connecticut, have invented a new, original, and ornamental Design for a Bed, of which the following is a specification, reference being had to the accompanying drawing, forming a part hereof.

The figure is a perspective view of a bed, showing my new design.

I claim:

The ornamental design for a bed, as shown.

SALVATORE BEVELACQUA.
